HIGH FREQUENCY CABLE

Ludwig Walter, Berlin, Germany, assignor to
Telefunken Gesellschaft für Drahtlose Tele-
graphie m. b. H., Berlin, Germany, a corporation
of Germany

Application November 17, 1931, Serial No. 575,556
In Germany November 22, 1930

2 Claims. (Cl. 173—264)

This invention relates to electric cables and more particularly to cables adapted for the transmission of high frequency currents.

The object of this invention is a special embodiment and form of construction of a high frequency cable. According to the present improvement the material used for insulating the inner conductor from the outer conductor consists of quartz wool or some similar elastic substance. The use of quartz wool is particularly recommendable whenever the inner and the outer conductors are flexible in nature inasmuch as the radio frequency cable can then be flexed as a whole just like a standard cable and can thus be easily wound or rolled up. Quartz wool furthermore constitutes a good insulator whose phase (angle) difference is of a particular order of magnitude for the frequencies here coming into consideration. The inner conductor may most

suitably consist of stranded wire, while the outer may consist, if desired, of a wire gauze or metal foil.

One embodiment of the invention is illustrated in the attached drawing where T the inner conductor, A the outer, and G the quartz wool.

I claim:

1. In a system carrying radio frequency currents, a flexible cable transmitting said currents, said cable comprising concentric inner and outer conductors, said conductors being insulated from each other by quartz wool.
2. In a system carrying radio frequency currents, a cable comprising inner and outer flexible conductors, said outer conductor being composed of wire gauze, the said inner conductor being composed of stranded wire, both of said conductors being insulated from each other by quartz wool.

LUDWIG WALTER. 20
